UNITED STATES PATENT OFFICE.

EUGENE F. TRENT, OF JERSEY CITY, NEW JERSEY.

LAMP.

SPECIFICATION forming part of Letters Patent No. 519,851, dated May 15, 1894.

Application filed September 20, 1889. Serial No. 324,500. (No model.)

To all whom it may concern:

Be it known that I, EUGENE F. TRENT, of Jersey City, in the county of Hudson and State of New Jersey, have invented a certain 5 new and useful Improvement in Lamps, of which the following is a specification.

I will describe a lamp embodying my improvement and then point out the novel features in the claims.

10 In the accompanying drawings Figure 1 is a central vertical section of a lamp embodying my improvement. Fig. 2 is a top view of the same. Fig. 3 is a horizontal section of the upper parts taken at the plane of the dotted line $x-x$ Fig. 1. Fig. 4 is a perspective view of one of a number of fingers which serve to center the outer air distributer, the outer deflector and the chimney. Fig. 5 is a side view of a wick carrier. Fig. 6 is a top view of the same. Fig. 7 is a side view of certain parts of the burner. Fig. 8 is a top view of the parts shown in Fig. 7. Fig. 9 is a sectional elevation of certain other parts of the burner. Fig. 10 is a top view of a wick carrier of modified construction. Fig. 11 is a sectional elevation of certain parts of a burner of modified construction. Fig. 12 is a horizontal section taken at the plane of the dotted line $y-y$, Fig. 11. Figs. 13, 14 and 15 are 20 enlarged views of certain parts of the lamp.

Similar letters of reference designate corresponding parts in all the figures.

A designates the fount of the lamp, which is represented as being made of sheet metal and as provided with a central tube B. As here shown there is a flaring cavity a, at the base of the tube B, and this cavity forms a funnel-shaped mouth which will be advantageous for directing air into the tube B. It 30 will be observed that the reservoir is provided at the center of its top with a mouth or collar a', adapted to receive a burner and that the tube B terminates approximately on a level with the top of this mouth or collar. The tube B is intended to serve as a central draft tube for a burner which is made detachable from the lamp fount. Its coaction with the burner can be more perfectly explained 40 after a description of the burner shall have 45 been given. As here shown the fount is supported upon a pedestal C, which is perforated

at the bottom so as to admit air within it and has inside it and beneath the tube B, a drip cup K. The fount A, as here shown, has a partition a², extending horizontally across it about midway between the top and bottom. This partition is represented as made of perforated material, as, for instance, perforated sheet metal. The partition has a central opening of sufficient size to allow the extension through it 55 of all the centrally located parts of the lamp which should pass below it. In the present instance this opening simply serves to permit the extension of the wick beneath the partition. Beneath the partition a², the fount is traversed 60 by a number of radial partitions a³, which extend from the outer wall nearly to the center and are made of perforated material, preferably perforated sheet metal. Above the partition a², the fount is traversed by a 65 number of partitions a⁴, which, like the partitions a³, extend from the outer wall inwardly nearly to the center. Preferably these partitions a⁴ will not be in line with the partitions a³, but will occupy positions intermediate of the partitions a³. The partitions a⁴, 70 like the other partitions, may be made of any suitable perforated material.

By the partitions described I am enabled to divide the fount into a number of compartments which, while they have free intercommunication, serve to check the movement of the oil within the fount and thereby reduce the liability of the spilling of any of the oil. A fount having compartments of this character is peculiarly adapted for use on any article in motion, as, for instance, in vehicles or marine vessels. The fount is shown as provided with a filling well a⁵, made of perforated sheet metal and having its mouth closed by 85 a removable cap. In it is an annular float which may consist of a piece of cork. An annular float is desirable because under the influence of a moving column of oil within the well it will not rock but will be rotated. 90

D designates a burner having a body d, which may be made of sheet metal and has a central boss which fits in the mouth or collar a', of the fount. In the present instance the boss is represented as externally screw-threaded and the mouth or collar as internally screw-threaded for effecting the en- 95 100

gagement of the burner with the fount. The body is shown as closed by a cap d' . Secured in the body are two cylindric shells d^2, d^3 , which are arranged the latter concentrically within the former at a sufficient distance from it to accommodate a wick. The outer shell d^2 , is secured by solder, or otherwise, to the burner body d , and the inner shell d^3 , is secured to the outer by upright plates d^4 , extending diametrically between the shells. These plates d^4 (see Fig. 2), may be secured by solder or otherwise, to the shells. These plates need not extend for a great distance lengthwise of the shells. When the wick tube is thus constructed of two shells united by diametrically extending plates, it is, of course, only adapted for a wick made in two sections, or, for a wick whose lower portion is divided. The inner shell d^3 , of the burner, extends down over the upper portion of the tube B , in the fount, fitting said tube closely. The tube B , will form a guide by which the screwing of the burner into the mouth or collar a' , of the fount, will be facilitated. Air ascending through the tube B , will pass into the inner shell d^3 , of the burner and ascend through the latter to the flame. It will be spread outwardly by spreaders $S' S^2$, supported by a post or pedestal sustained by spiders connected with the inner shell.

E designates the wick carrier. As represented in the principal example of my improvement, more particularly in Figs. 5 and 6, it consists of a band of sheet metal having a number of V-shaped incisions, the metal bounded by which is pressed inward to form prongs adapted to engage with the wick. It will be seen that this ring has L-shaped incisions made at one end, in the present instance at the lower end, and that the metal bounded by these incisions is turned inwardly to form projections e , constituting partitions which indicate the position which the edges of the sections or portions of wick should occupy and for facilitating the proper insertion of said sections or portions. These projections e are approximately in line with the plates d^4 , extending diametrically between the two shells of the wick tube. On the exterior of the band are pins or projections e' , which pass through vertical slots located diametrically opposite each other in the upper portion of the outer shell d^2 , of the wick tube, so that they may be moved up and down to elevate and lower the carrier and with it the wick.

Outside the outer shell d^2 , of the wick tube, is a tube F , having spiral slots into which the projections e' extend. This shell is free to rotate to cause its spiral slots to elevate and lower the pins and hence the wick carrier and wick. At the lower end this tube F , loosely surrounds an upwardly turned flange with which the top or cap d' , of the burner body d , is provided, and from its lower end extends a flange f , the outer portion of which

is depressed to form a shoulder f' , and a hand-piece f^2 , which may be grasped to effect the rotation of the tube. It will be seen that the top or cap d' , of the burner body has a shouldered portion corresponding to the shoulder f' and receiving the latter around it in such a manner as to aid in centering the tube F . The upper end of the tube F is provided with an inwardly and downwardly extending flange f^3 , which may be made by turning the upper edge of said tube inward and downward. The upper end of the outer shell d^2 of the wick tube is turned outwardly into contact with the interior of the main portion of the tube F and the flange f^3 overlaps it. The flange f^3 in combination with the outer shell d^2 of the wick tube, forms outside the wick, a bell-mouth or funnel, which will catch any oil overflowing from the exterior of the wick and convey it back into the wick tube. The upper outturned edge of the outer shell of the wick tube in connection with the flange f^3 also aids in centering the tube F relatively to the outer shell of the wick tube. The tube F is only held in place by friction and hence may with its flange f and hand-piece f^2 , be lifted off the cap or top of the burner body and outer shell of the wick tube. In the flange f , opposite the spiral slots, radially extending slots are provided and these communicate with the spiral slots, so as to enable the projections e' of the wick carrier, to enter the spiral slots. I desire to call attention to the fact that the upper edge of the tube F extends above the outer shell of the wick tube and forms the tip of the outer wall of the wick tube.

G designates the air distributer, here shown as made of cylindric form with an expanded base portion g' and an expanded top portion g^2 . The expanded base portion fits around the shouldered portion f' of the flange f appended to the tube F . On the shouldered portion f' are a number of bosses or projections f^4 . These fit within the expanded base portion of the air distributer G , and center the same. On the shoulder f' , are other projections or bosses f^5 , which are lower than the projections f^4 . The expanded base portion of the air distributer has a corresponding number of cavities which may interlock with these lugs f^5 , so that any rotary movement of the air distributer or tube F , will be transmitted to the other. As the projections f^5 are lower than the projections f^4 , the air distributer may be centered properly by the projections f^4 , before it descends to a point low enough to interlock with the projections f^5 . The air distributer may be detached by simply lifting it off the flange of the tube F .

At the upper end of the air distributer G , are a number of fingers H , consisting of body portions h' , prongs h^2 adapted to extend through holes in the air distributer, horizontal portions h^3 , downwardly extending portions h^4 , having a bearing inside the air distributer,

tongue portions h^5 constructed to bear against the tube F, and upright portions h^6 serving to hold in place a deflector I, resting at the lower edge on the horizontal portions h^3 , and to sustain a chimney. The fingers may be secured to the air distributor by solder, or otherwise. In the present instance it will be seen that the downwardly extending portions h^4 , bear in a recess located at the upper end 5 of the air distributor. When they have such a bearing it will be sufficient to fasten the fingers merely by upsetting or riveting the ends of the prongs h^2 , outside the air distributor. These fingers aid in centering the air distributor relatively to the tube F and consequently relatively to the wick tube. They also serve to support and center the deflector I. If the prongs h^2 , are left sufficiently long, they will serve to support a shade holder or 10 globe holder. In Fig. 1, I have represented the lower part of a shade holder or globe holder, J, supported by the prongs.

Having now described the principal example of my improvement, I will describe the 25 parts of modified construction illustrated by Figs. 10, 11 and 12. In the burner illustrated by these figures, the bottom of the inner shell, d^3 , is closed, the body, d, of the burner is perforated and air is admitted from the interior 30 of the body to the interior of the inner shell d^3 , by horizontally extending tubes d^{10} , of which there may be any suitable number but are here represented as being only two in number. The wick carrier, E, instead of having merely two prongs e, has two pairs of prongs. They may be made in the same manner as the prongs e, first described. The reason why two pairs of prongs instead of two prongs are here used, is because the edges 35 of the sections or portions of the wick must be separated to straddle the tubes d^{10} . The inner shell, d^3 , of the wick tube is shown as extended inwardly or reduced in diameter near the tip. The outer shell, d^2 , is turned 40 outwardly and against its upturned edge fits the tube F. The tube F, is reduced in diameter at the upper portion. It will be understood that the upper portion of the tube F, forms a part of the wick tube in this example of my improvement as well as in the other 45 example of the improvement. The reduction of the shell d^3 and tube F, decreases the circumferential space in which the tip of the wick is accommodated, to such an extent that 50 the side edges of the wick sections or portions will come together and form a continuous wick at this point. At the upper extremity the tube F, is turned outwardly so as to form a bell mouth or funnel, by which any oil over- 55 flowing from the tip of the wick will be conveyed back into the wick tube. The tube F, is provided at the base with a flange f, a shouldered portion f' , and a hand-piece f^2 , as in the first example of my improvement. It also has spiral slots engaging projections e', 60 extending from the wick carrier through vertical slots with which the shell d^2 is provided.

To prevent a frictional bearing of the adjacent top edges or corners of the wicks, when forced upwardly within the reduced portions 70 of the wick tubes, I provide wings at the upper end of the tube d^3 . Said wings d^{12} are opposite each other and stand outwardly or at right angles to the longitudinal axis of the tube. As before stated these wings prevent 75 the corners of the wicks touching each other and also form guides to keep the upper portions of the wicks in an upright position.

In my pending applications, Serial Nos. 257,524 and 323,057, I show and claim wick 80 raising mechanism similar to that shown herein, but in this application I do not claim the wick raising mechanism in the combination as claimed in the applications above referred to. 85

What I claim as my invention, and desire to secure by Letters Patent, is—

1. In a lamp, the combination with the fount of a horizontal perforated partition and two sets of radial perforated partitions 90 respectively above and below the horizontal partition, substantially as specified.

2. In a lamp, the combination with the fount of a horizontal perforated partition and two sets of radial perforated partitions 95 respectively above and below the horizontal partition, one set of radial partitions being opposite the spaces between the other set of radial partitions, substantially as specified.

3. The combination with a wick tube having the upper edge of its outer shell turned outwardly, of a rotary tube having a bearing against the out-turned edge of the outer shell of the wick tube and forming a support for the wick at the upper end of the wick tube, 100 substantially as specified.

4. The combination of a burner body having a shouldered top or cap, a wick tube having the upper edge of its outer shell turned outwardly and a rotary tube having a bearing upon the shouldered portion of the top or cap of the burner body and a bearing against the out turned edge of the outer shell of the wick tube and forming a support for a wick at the upper end of the wick tube, 105 substantially as specified.

5. The combination with the outer shell of a wick tube having its upper edge turned outwardly, of a rotary tube having its upper edge turned inwardly so as to overlap the out turned upper edge of said outer shell of the wick tube and forming a support for the upper portion of a wick, substantially as specified. 115

6. The combination of the rotary tube F, 120 provided with two sets of projections f^4 , f^5 , the latter being lower than the former, and the air distributor D, centered by the projections f^4 , and interlocked with the projections f^5 , substantially as specified. 125

7. The combination with the air distributor, D, of the fingers H having upright portions h^6 , horizontal portions h^3 , downwardly extending portions h^4 , tongues h^5 and prongs h^2 130

extending through the air distributer, substantially as specified.

8. The combination with the air distributer D, of the fingers H having upright portions h^6 , horizontal portions h^3 , downwardly extending portions h^4 , and tongues h^5 , substantially as specified.

9. The combination with a wick tube, of a wick carrier provided with inwardly turned prongs e, substantially as specified.

EUGENE F. TRENT.
